DRIVE THRU MARKET

Herbert H. Blankenship, Houston, Tex.

Application May 23, 1956, Serial No. 41,611

Term of patent 14 years

(Cl. D13—1)

Fig. 1 is a front perspective view of a drive thru market, showing my new design, the rear being identical; Fig. 2 is a cross-sectional view thereof taken on line 2—2 of Fig. 1; Fig. 3 is a top plan view to a smaller scale; and Fig. 4 is an end elevational view also to a smaller scale.

I claim:

The ornamental design for a drive thru market, as shown and described.
